Charles J. Kintner

UNITED STATES PATENT OFFICE.

CHARLES J. KINTNER, OF NEW YORK, N. Y.

SOUND-REPRODUCING DEVICE.

SPECIFICATION forming part of Letters Patent No. 690,368, dated December 31, 1901.

Application filed January 21, 1898. Serial No. 667,466. (No model.)

To all whom it may concern:

Be it known that I, CHARLES J. KINTNER, a citizen of the United States, residing at New York, in the county of New York and State 5 of New York, have made a new and useful Invention in Sound-Reproducing Devices, of which the following is a specification.

My invention is directed particularly to a novel sound-reproducing device; and to this 10 end it consists in constructing a record-blank of spherical form and combining therewith means for rotating the record and advancing the stylus thereover.

For a full and clear understanding of the 15 invention, such as will enable others skilled in the art to construct and use the same, reference is had to the accompanying drawings, in which—

Figure 1 is a side elevational view of my 20 invention complete, and Fig. 2 is a sectional view taken through Fig. 1 on the lines xx and as seen looking thereat from right to left.

A is the base, M the motor-box, and S' the 25 shaft connected to the motor and supporting the phonogram-blank, constructed, preferably, of wax and in the form of a sphere P. The outer end of the shaft is journaled in a standard V, pivotally secured to the base A at p and provided with a lock or latch l for 30 locking it in its upper position.

m and m are vertical standards provided at their upper ends with inwardly-extending trunnions t t .

a a are the arms of a yoke to the upper 35 surface of which is secured the diaphragm-supporting chamber N, t being the stylus, T the sound-conveying tube, and T' the trumpet.

w w are counterweights secured by screw- 40 threads to the lower ends of the arms a a , and f f are pivot-bearings adapted to support the arms a a upon the trunnions t t .

The operation of the apparatus is as follows: The standard V is unlocked and tilted 45 to the left in the direction of the lower arrow and the record or phonogram-blank P placed in position upon the conical mandrel. (Shown in dotted lines.) The standard V is then restored to its normal position and locked by 50 the latch l . The diaphragm-chamber N and its attached parts, consisting of the dia-

phragm, (not shown,) and the stylus t , and sound-conveying tube T, and trumpet T', are then secured to the arms a a and the latter hung upon the trunnions t t in the extreme 55 right-hand position, or so that the mouth of the trumpet is near the top of the motor-box, with the counterweights w w extending outward to the left. After the proper adjustment is attained between the stylus t and the 60 record the motor is set in motion and the spiral-like nature of the record causes the parts to advance in the direction of the upper arrow, thereby correctly reproducing the sounds in a manner well understood, the stylus 65 t traveling always in a great circle of the spherical record and bearing, therefore, a constant relation to the record.

I do not limit my invention to the special detail of construction hereinbefore described, 70 and illustrated in the accompanying drawings, as I believe I am broadly entitled to claim a phonographic record of spherical form, and my claims are generic as to this feature and also to a record of spherical form 75 with means for rotating the same.

Having thus described my invention, what I claim, and desire to secure by Letters Patent of the United States, is—

1. The improved record-blank for talking- 80 machines comprising a record-blank having a spherical surface.

2. The combination with a stylus in a sound-reproducing machine of a rotary spherical record and means for causing the stylus to trav- 85 erse the spherical surface of the record.

3. A phonograph or sound-reproducing device having a spherical-shaped record provided with means for rotating it about one axis of the sphere, in combination with a re- 90 producing-stylus pivotally supported substantially at right angles to the axis of rotation, whereby the stylus is adapted to travel in the arc of a great circle on said spherical record.

4. A phonograph or sound-reproducing de- 95 vice provided with a spherical-shaped record, in combination with reproducing means so supported in connection with said record as to travel in the arc of a great circle thereof. 100

5. A phonograph or sound-reproducing de- vice having a spherical-shaped record and

means for rotating the same, in combination with reproducing means so supported with relation to the surface of the record that the stylus thereof will travel in a great circle 5 thereof, passing through the plane of its axis of rotation.

In testimony whereof I have hereunto sub-

scribed my name this 20th day of January, 1898.

CHARLES J. KINTNER.
